Primary Examiner — Sheryl Lane*Assistant Examiner* — Nicole C Shiflet(74) *Attorney, Agent, or Firm* — Bereskin & Parr LLP**CLAIM**

We claim the ornamental design for a musical instrument, as shown and described.

DESCRIPTION

FIG. 1 is a perspective view of the musical instrument embodying the design;

FIG. 2 is a front view thereof;

FIG. 3 is a back view thereof;

FIG. 4 is a top view thereof;

FIG. 5 is a bottom view thereof;

FIG. 6 is a left side view thereof; and,

FIG. 7 is a right side view thereof.

The broken lines represent environmental structure and form no part of the claimed design.
